[57] **CLAIM**

The ornamental design for a combined cleaning fluid spray container and rolled towel support, as shown and described.

DESCRIPTION

FIG. 1 is a side elevational view of a combined cleaning fluid spray container and rolled towel support showing my new design, the opposite side being a mirror image of that shown; and,

FIG. 2 is a top plan view thereof, the bottom being plain and unornamented. The broken-line showing of the sprayer head and rolled towels being for illustrative purposes only and forming no part of the claimed design.
